JOHN W. LESLIE, OF SOUTH PASS, ILLINOIS.

Design No. 4,359, dated September 20, 1870.

DESIGN FOR BERRY-BOXES.

The Schedule referred to in these Letters Patent and making part of the same.

To all whom it may concern:

Be it known that I, JOHN W. LESLIE, of South Pass, in the county of Union and in the State of Illinois, have invented a new and useful Design in Berry Boxes; and do hereby declare that the following description, taken in connection with the accompanying drawing hereinafter referred to, forms a full and exact specification of the same, wherein I have set forth the nature and principles of my said improvement, by which my invention may be distinguished from others of a similar class, together with such parts as I claim and desire to secure by Letters Patent.

The nature of my design is fully represented in the accompanying drawing, to which reference is made. I claim as my invention—
The design for a berry-box, as shown.
In testimony that I claim the foregoing, I have hereunto set my hand this   day of   1870
